ATTORNEY.

UNITED STATES PATENT OFFICE

137,414

DESIGN FOR A MARINE CABLE TOOL

Walter Tomsick, Los Angeles, Calif.

Application January 3, 1944, Serial No. 112,164

Term of patent 14 years

To all whom it may concern:

Be it known that I, Walter Tomsick, a citizen of the United States, residing in Los Angeles, in the county of Los Angeles and State of California, have invented a new, original, and ornamental Design for a Marine Cable Tool, of which the following is a specification, reference being had to the accompanying drawing, forming part thereof.

Fig. 1 is a perspective view of a marine cable tool showing my new design.

Fig. 2 is a side view of said marine cable tool.

Fig. 3 is an edge view of said marine cable tool.

I claim:

The ornamental design for a marine cable tool, substantially as shown.

WALTER TOMSICK.
